MAGNETIC CORE CIRCUIT

John C. Mallinson, Harrisburg, Pa., assignor to AMP Incorporated, Harrisburg, Pa., a corporation of New Jersey

Filed Oct. 11, 1961, Ser. No. 144,370
5 Claims. (Cl. 340—174)

This invention relates to an information storage and shifting circuit using magnetic cores.

An object of this invention is to provide an improved arrangement for shifting information stored in one core to another core.

A further object is to provide a magnetic core shift register having improved stability and operating temperature range.

These and other objects will in part be understood from and in part pointed out in the following description.

In a multi-aperture magnetic core (MAD) shift register, such as disclosed in U.S. Patent No. 2,995,731, a minor transmitting aperture of one core is connected via a coupling loop to a corresponding receiving aperture of the next core, and so on. Information, in the form of magnetic flux stored in one core, is transmitted to the next core by a current generated in the coupling loop between them when the magnetic flux in the transmitting core is reversed by the application of an advance drive current.

Now one of the problems with such a circuit is the difficulty of obtaining MAD cores having the proper electromagnetic and other physical characteristics within sufficiently close limits. Unless the cores in a register are reasonably uniform and within close enough tolerances to the necessary values, the register will operate poorly, or not at all. This is particularly true where the register is subjected to wide changes in temperature. The present invention to a large extent overcomes these problems.

In accordance with the present invention, in one specific embodiment thereof, a MAD core shift register, similar to the one described in the aforesaid patent application, is provided with additional toroidal magnetic cores inserted in the respective coupling loops of the register. These additional cores, which are relatively inexpensive, are carefully tailored to match certain of the characteristics of the MAD cores in the register. As a result MAD cores which otherwise could not be used in a satisfactory register, now become fully operative over a wide range of temperature. The toroidal cores are easily inserted in the circuit so that the cost of providing them is practically as low as the small price of the cores themselves.

A better understanding of the invention together with a fuller appreciation of its many advantages will best be gained from a study of the following description given in connection with the single FIGURE of the accompanying drawing which is a schematic circuit of a shift register embodying features of the invention.

The shift register 10 shown in the drawing includes an odd numbered ("O") core 11 and an even numbered ("E") core 12, each of which is made of magnetic ferrite material. Core 11 has a central aperture 13 which is coupled by an advance "O" drive winding 14. Similarly, core 12 has a central aperture 16 which is coupled by an advance "E" winding 18. O core 11 has a minor output or transmitting aperture 20 which is threaded by a coupling loop 22, this loop also threading a minor input aperture 24 of E core 12. In the same way core 12 has an output aperture 26 which is threaded by a coupling loop 28 which may be the output winding of the register or which may extend to another core (not shown).

Threading output apertures 20 and 26 is a prime winding 30. The purpose of this winding is to apply

2

a current to condition or "prime" the flux at a transmitting aperture prior to the occurrence of a drive current pulse on the respective advance winding threading a core. The prime winding is in series with advance windings 14 and 16 and when an advance current is applied to either of these, this current also flows in prime winding 30. These operations are explained in greater detail in the aforesaid patent.

Now, it will be noted that coupling winding 22 also threads a toroidal magnetic core 32. This auxiliary core is proportioned so that its number of flux linkages (i.e. its remanent flux times the number of coupling loop turns through the core) are equal or slightly greater than the number of elastic flux linkages of transmitting minor aperture 20. Core 32 is also threaded by prime winding 30. Similarly, coupling winding 28 is threaded by another toroidal core 34 itself also threaded by prime winding 30.

Assume that the flux in the outer leg of O core 11 at aperture 20, which leg is encircled by coupling winding 22, is saturated with flux in the downward or clockwise direction. This condition represents a binary "zero" stored in the core. Then on the occurrence of a current pulse on ADV O drive winding 14 (which current will be in a direction tending to set the flux in the core in the clockwise direction), the only flux switched in the outer leg of the core under winding 22 will be elastic flux since this outer leg is already saturated with flux in the clockwise direction. This switching of elastic flux, however, generates a voltage which will tend to cause a noise current to flow in winding 22. Simultaneously, though, the advance current flowing in winding 14 (which current is switching elastic flux in core 11) flows in prime winding 30. Now, winding 30 threads auxiliary core 32 in a direction such that the advance current switches remanent flux in the core in the clockwise direction. The switching of this remanent flux generates a voltage in coupling winding 22 which opposes and effectively cancels the elastic flux voltage induced in the winding at core 11. In this arrangement, the switching of flux in auxiliary core 32 is not determined by current flow in coupling winding 22. Here, therefore, the noise voltage can be almost exactly cancelled by the voltage from auxiliary core 32. Accordingly, virtually no "noise" current will flow in winding 22. This means, among other things, that the resistance of this winding can be reduced with the result that a binary "one" can be more easily transmitted to core 12.

A short time after an advance current occurs on winding 14 and prime winding 30, a prime current will be applied to the latter. This current is in a reverse direction relative to an advance current. It therefore drives the flux in auxiliary core 32 into saturation in the counter-clockwise direction. Thus this core is automatically conditioned for the next transmission of a "zero" or a "one," as described above. Auxiliary core 34 functions in the same way as core 32, but on the occurrence of an advance E to O drive current.

The material from which cores 32 and 34 are made is not critical. They can be made of the same ferrite material as cores 11 and 12, if desired. In one ten bit shift register, which has been built and successfully operated, the auxiliary cores were approximately as large as the portion of core 11 surrounding output minor aperture 20. In certain instances it may not be necessary to provide an auxiliary core with each coupling loop of a multi-bit shift register.

The above description is given in illustration and not in limitation of the invention. Various changes or modifications in the embodiment described may occur to those skilled in the art and these can be made without departing from the spirit or scope of the invention as set forth.

I claim:

1. In a magnetic core information storage and transfer circuit: a first multi-aperture magnetic core having a minor output aperture, a second magnetic core, drive winding means linking said first core to saturate it with flux in a clear direction, means to set said first core with information, prime winding means threading said minor output aperture, said prime winding means being in series with at least a portion of said drive winding means, a coupling winding threading said output aperture and said second core, and an auxiliary magnetic core threaded by said coupling winding and said prime winding means, said auxiliary core having a flux content approximately equal to the elastic flux switched around the output aperture of said first core.

2. The circuit in claim 1 wherein said auxiliary core is proportioned to induce in said coupling winding a voltage substantially cancelling the elastic flux voltage induced therein by said first core.

3. A circuit of the character described comprising a plurality of multi-aperture magnetic cores, drive means threading said cores to drive them respectively to clear state, a coupling loop threading a minor output aperture of one core and an input aperture of the next core to transfer information, and a small toroidal core 20 threaded by said coupling loop and said drive means, said toroidal core having a remanent flux content just slightly

10 15 larger than the elastic flux switched around the minor output aperture of said one core.

4. In an information shifting circuit of the character described, a plurality of multi-aperture magnetic cores, respective advance drive means threading said cores in even and odd groups to advance information stored in the cores of one group to the next cores respectively in the other group and so on, means to set information into an initial core of the circuit, coupling loops each threading a respective minor output aperture of a core of one group and an input aperture of a core of the next core of the other group, a prime winding threading each said output minor aperture to reverse flux set locally therearound, said prime winding being in series with said advance drive means, and at least one magnetic core linking one of said coupling loops and said prime winding.

5. The circuit in claim 4 wherein each of said coupling loops threads the corresponding minor output aperture twice, threads an input minor aperture of the next core once, and threads the corresponding toroidal core once, said toroidal core having a flux content approximately equal the elastic flux switched at said minor output aperture, said toroidal core setting before said next core sets.
